STACKING DEVICE

Sebastian Camerano, Clinton, Mass.

Application May 2, 1950, Serial No. 159,597

1 Claim. (Cl. 271—86)

1

This invention relates to new and improved devices for stacking and cooling waxed or coated envelopes and bags, special reference being had to envelopes and bags which are used to contain potato chips, corn chips and other greasy food materials and the like.

In the making of envelopes or bags of waxy paper or coated paper, such envelopes or bags issue from the forming machine in a heated condition so that when stacked immediately they tend to adhere to each other as they cool and the larger the stack, the more pressure is created thereon and thus the adherence between the separate bags or envelopes becomes worse.

This invention is a continuation in part of my prior application, Serial No. 137,652, filed January 9, 1950; and the principal object of the present invention is to provide improved mechanism for controlling the speed of the conveyor carrying the envelopes or bags while they cool and before stacking; the provision of an initial feeding means or transfer device provided with power operated means in the form of belts for receiving the bags or envelopes from the forming machine and positively feeding the same to the guide plate, the latter being stepped and arranged at an angle to the longitudinal direction of advance of the bags or envelopes from the forming machine, said device being operated by a separate motor and preferably being provided with means for controlling the speed thereof; and the provision of simplified and novel adjustable stop means to position the leading edge of the bags or envelopes as they issue onto said conveyor from the power operated feed device.

Other objects and advantages of the invention will appear hereinafter.

Reference is to be had to the accompanying drawings in which

Fig. 1 is a perspective view of a machine according to the invention;

Fig. 2 is a view in side elevation thereof, parts being omitted;

Fig. 3 is a section on line 3—3 of Fig. 2 as shown in Figs. 1 and 2.

This invention comprises principally a conveyor 10 which in the disclosure herein is embodied in a rotating circular table supported on a column 12 which in turn is supported on a base 14 of any desired or convenient construction. The column 12 carries a vertical shaft 16 driven at a low rate of speed through a reducing gear box 18, the gear box being driven by a pulley 20 connected to a variable diameter pulley 22, this pulley being of the Reeves type and mounted on the drive shaft of a motor 24.

10 The motor 24 is mounted on a pivoted bed 26 having pivot pins 28 supporting the same on a ring 29 on the column 12 and the plate 26 being arc-shaped as at 30 to accommodate the column 12. The bed 26 has an arm 32 extending to the opposite side of the column 12 and receiving adjusting device 34 which in this case assumes the form of a threaded rod journaled in the ring 29. As the threaded rod 34 is turned, it pivots arm 32 and hence bed 26 so that the motor 24 is moved upwardly or downwardly depending on the direction of rotation of the screw shaft 34. As the motor moves up, the Reeves type pulley 22 spreads to provide a smaller diameter to slow down the rotation of the table 10 and, of course, the opposite effect takes place upon lowering the motor 24.

20 A large collar 36 is secured in rotatively adjustable position on the column 12. A tube 38 extends radially outwardly from the collar 36 and slidingly receives a rod 40 supporting a vertical rod 42 in vertically adjustable position. Rod 42 has a motor and plate 44 secured thereto and at its upper end it carries a frame 46 in which 25 are journaled a pair of rollers as at 48. These rollers are provided with belts 50 and are driven by a motor as by a belt 52. This arrangement forms a power-driven positive transfer device from the envelope or bag forming machine to the ledge guide indicated at 54 and more fully shown and described in my aforementioned co-pending application. A control 55 may be used to control the speed of motors 44 and 24 together if desired.

35 It is to be noted that the rod 42 may be adjusted vertically so as to reposition frame 46 where desired and rod 40 may be adjusted radially providing a very flexibly arranged takeoff device for the envelopes. A wire hold-down device 56 may be mounted on the frame 46 so as 40 to ensure aligned progress of the bags or envelopes to and down the guide 54.

Another collar 58 is mounted on the column 12 below collar 36 and this collar mounts a rod 60 in general radial relation to the column 12. At its outer end rod 60 vertically adjustably mounts a vertical rod 62 on which is mounted a rod 64 rotatively adjustable thereon. The rod 64 in turn mounts a stacking board 66 against which the bags or envelopes 68 move against and become stacked, table 10 moving in the direction of the arrow, see Fig. 1. Of course, the waxed bags are cooled by the time they run up on the stacking board 66.

55 Rod 62 mounts another adjustable rod 68 which extends over the table 10 and adjustably carries

a vertical pin or rod 70 against which the bags impinge and are stopped as they are directed from the transfer device 46 down the guide 54.

This stop pin 70 is easily adjustable radially of the table 10 to take care of different sizes of bags or envelopes and require them to stop uniformly as clearly shown in Fig. 1. The rod 62 may also be utilized to adjustably support a curved table edge guide 72 which prevents the envelopes from sliding off the table when they are being stacked 10 against the board 56.

Having thus described my invention and the advantages thereof, I do not wish to be limited to the details herein disclosed otherwise than as set forth in the claim, but what I claim is:

Apparatus of the class described comprising a table, variable speed means to rotate the table, an article feeding device radially arranged above the table, means to cause the feeding device to operate at a certain speed, means to vary the 20 speed of rotation of the table relative to the speed

of the feeding device, radially adjustable stop means in the path of the articles rising from the feeding device, said stop means being above the table, and a stacking device above the table angularly spaced from the feeding device in the direction of rotation of the table.
